Patented June 26, 1928.

UNITED STATES PATENT OFFICE.

ERNEST FLAGG, OF NEW YORK, N. Y.

HINGE.

Original application filed February 4, 1926, Serial No. 86,041. Divided and this application filed June 8, 1926. Serial No. 114,506.

This invention relates to a new and improved form of hinge.

An object of the invention is to provide a hinge which is simple, durable and strong and made of a minimum number of parts capable of supporting a maximum weight of door with a minimum defacement of the door and a minimum liability of becoming loosened.

10 This application is, with the exception of the modified form of hinge shown in Fig. 4, a division of my application Serial #86,041, filed February 4, 1926.

The invention is illustrated in the drawings, of which—

Figure 1 is a horizontal section through the door and the jamb showing the hinge in plan view;

Figure 2 is a front elevation of the hinge; 20 Figure 3 is a section taken on the line 3—3 of Figure 1;

Figure 4 is a section through a modified form of the hinge.

The form of the invention shown in the drawings is a preferred form, although it is understood that modifications in the construction and arrangement of the parts and in the character of materials used may be adopted without departing from the spirit 30 of the invention as set forth in the appended claims.

In its general aspect the invention comprises a pair of plates that are adapted to be disposed in the door and the jamb, at 35 right angles to the vertical surfaces thereof, these plates having on their inner ends integral turned up cylindrical portions adapted to be disposed in a suitable bore formed in the body portion of the door and the jamb and through which cylindrical portions fastening means such as nails and screws may be introduced into the door and the jamb.

The outer ends of these plate portions, which project beyond the body portion of 45 the door and the jamb are provided with roller bearing casings in the form of cup-shaped housings which are adapted to receive a roller bearing to permit the two members of the hinge to freely move with 50 respect to each other with as little friction as possible.

In the preferred form of the invention shown in the drawings, the hinge comprises a pair of plates 10 and 11 which on their 55 inner ends are provided with integrally

turned up cylindrical portions 12 and 13, the axes of which are parallel to the front surfaces 14 and 15 of the door and the jamb. Suitable fastening means such as screws 16 and 17 may be introduced through the cylindrical portions to hold the plates in position. The main body portions of the plates 10 and 11 are disposed in sawcuts 18 and 19, formed in the surface of the door and the jamb. The outer ends of the plates are 60 formed as cup-shaped casings or housings 20 and 21 cooperatively defining a container for a roller bearing unit. The lower housing 21 is provided with an upstruck hub 22 on which the inner member 23 of a roller bearing unit is centered. This inner element of the roller bearing unit is in contact with the upper casing 20. The outer element 24 of the roller bearing unit is in contact with the upper casing 20 and between these two 70 elements are a series of balls 25. A split bayonet pin 26 connects the two casings being passed through central aligned apertures therein to hold them together.

75 The hinge of Fig. 4 is substantially the same as that described above, except that instead of using the bayonet pin, I have connected the two cup-like housings 20 and 21 by a double headed sectional stud passed through the aligned central apertures in the 80 housing sections. This stud, designated by the reference character 30 is formed with an integral head 31 at one end, and with a reduced threaded extension 32 at the other end, upon which a second head 33 is removably secured.

85 Therefore, in applying the hinge it is necessary to provide two sawcuts in the corners of the door and the jamb and then to drill a bore in the edge of each of these members 90 as shown. These bores, however, are not ordinarily visible, since they are formed in the edges of the door and the jamb.

95 This hinge is light and yet exceedingly strong and will operate with a minimum of friction.

100 What I claim is:

1. A hinge construction which comprises a pair of hinge plates having cup-shaped casings on their outer ends adapted to lie with their open faces abutting each other, a hub formed on the inner face of one of said casings, a roller bearing unit comprising an inner and an outer element with intervening 105 balls, the inner element adapted to embrace 110

the hub and bear thereagainst, the outer unit adapted to lie within said casings and support the upper casing.

2. A hinge construction which comprises a pair of hinge plates having cup-shaped casings on their outer ends adapted to lie with their open faces abutting each other, a hub formed on the inner face of one of said casings, a roller bearing unit comprising an inner and an outer element with intervening

balls, the inner element adapted to embrace the hub and bear thereagainst, the outer unit adapted to lie within said casings and support the upper casing, said casings having aligned apertures and a split bayonet fastening pin extending between the casings through said apertures to hold the casings together. 15

ERNEST FLAGG.
